UNITED STATES PATENT OFFICE.

JOHN C. BARBER, OF ST. PAUL, MINNESOTA.

CAR-TRUCK.

SPECIFICATION forming part of Letters Patent No. 573,636, dated December 22, 1896.

Application filed April 29, 1896. Serial No. 589,589. (No model.)

To all whom it may concern:

Be it known that I, JOHN C. BARBER, a citizen of the United States, residing at St. Paul, in the county of Ramsey and State of Minnesota, have invented certain new and useful Improvements in Car-Trucks; and I do hereby declare the following to be a full, clear, and exact description of the invention, such as will enable others skilled in the art to which it appertains to make and use the same.

My invention relates to that class of car-trucks wherein the truck-bolster is mounted with freedom for vertical and lateral motion, and has for its object to improve the construction with a view of increased economy and efficiency.

To these ends my invention comprises the novel devices and combinations of devices hereinafter described, and defined in the claims.

My invention is illustrated in the accompanying drawings, wherein, like letters referring to like parts throughout the several views—

Figure 1 is a side elevation of my improved truck. Fig. 2 is a plan view of one half of the truck, the other half being broken away. Fig. 3 is a vertical section, partly on the line $x^3 x^3$ of Fig. 2 and partly in a vertical plane, through the center of the truck-bolster and one of the side frames. Fig. 4 is a perspective view, with some parts broken away, showing one of the side frames and parts coöperating therewith. Fig. 5 is a perspective view, with some parts broken away, showing one end of the truck-bolster with some parts removed and others broken away. Fig. 6 is a detail in perspective, showing one of the bolster end caps or filling-pieces removed. Fig. 7 is a detail in horizontal section, taken through a portion of the truck-bolster on the line $x^5 x^5$ of Figs. 1 and 3. Fig. 8 is a detail in plan, showing one of the movable plates which are carried with the bolster in its lateral movement; and Fig. 9 is a view in horizontal section corresponding to Fig. 7, but illustrating a slight modification in the form of the guides for the movable bearing-plates.

For the purposes of this case the details of the side frames of the truck are immaterial. The truck-frame may be of any suitable construction so long as the truck-bolster is mount-

ed thereon with freedom for vertical and lateral movement.

In the truck illustrated in the drawings, a represents the wheels; a' , the axles; a^2 , the journal-boxes; a^3 , the journal-box guides, and a^4 the tie-bolts, working through said guides a^3 and the bars b b' b^2 , which together constitute the side frames of the truck. Of the said side-frame bars b b' b^2 the upper member b is of channel form and the other two members b' and b^2 are plain bars, as best shown in Figs. 3 and 4.

The transoms c are shown as of channel-bar form and are riveted or otherwise secured to the bolster-columns c' . The said bolster-columns c' are also composed of channel-bars and are rigidly secured by gussets c^2 to saddle-plates c^3 , of channel form, which rest upon the side-frame bars b' and b^2 . Column-bolts c^4 extend through all the parts b b' b^2 and c c' c^3 for rigidly securing the same together, relative to each other, in their proper working positions. The said transoms c , bolster-column c' , and saddle-plate c^3 are conveniently made from channel-bars of the same size, with the inner flanges of the column c' cut away to permit the transoms to be seated against the bolster-columns. The saddle-plates c^3 are cut away or notched at their ends to afford the necessary clearance for the inclined parts of the truss-bars b' .

On the saddle-plates c^3 rest channel-bar roller-bearing plates f , which are of the proper size to fit against the bolster-columns c' , with their flanges engaging over the flanges of the said saddle-plates c^3 . In this way the said bearing-plates f are held in a fixed position. Roller-bearings f' rest in concave seats extending longitudinally of the said fixed bearing-plates f . On the said rollers f' are mounted movable plates f^2 , which have on their under surface concave seats engaging with the rollers f' and have on their upper surface spring-seats f^3 . Springs f^4 rest on the said plates f^2 , and on the said springs rest shimming-blocks f^5 , which support the bolster. The said bolster is composed, as shown, of channel-bars g , connected by the center plate g' , end cross-ties g^2 and g^3 , and end caps g^4 , which fit between the ends of the channel-bars and the tie-bars g^2 and are riveted or otherwise rigidly secured

thereto, as shown in Figs. 1, 2, 3, and 7. The channel-bars g , of which the bolster is made, are preferably set with their flanges facing inward or toward each other, and near the outer ends of the bolster the lower flanges of the said channel-bars g are cut away, as best shown in Figs. 3, 5, and 7, so as to afford clearance for the vertical movement of the bearing-plates f^2 and the bolster relative to each other. As shown in Figs. 1 to 8, inclusive, the said movable bearing-plates f^2 are provided with notches f^6 , and the bolster channel-bars g are provided with vertical guides g^5 , cooperating with the said notches f^6 to carry the said plates f^2 with the bolster in its lateral movement, while permitting the bolster to move up and down in respect to said plates.

In the modification shown in Fig. 9 the substitute movable bearing-plates h are represented as cooperating with vertical guides h' , of angle-iron form, riveted or otherwise secured to the bolster channel-bars g and engaging with the corners of the said plates h . It must be obvious that the said movable plates f^2 might be held and guided in respect to the bolster in any other suitable way.

The shimming-blocks f^5 are shown as tied to the bolster by nutted bolts f^7 , passing through the said blocks and the tie-bars g^3 of the said bolster. The said shimming-blocks f^5 are also represented as provided with plates f^8 on their under surface for resting on the springs f^4 , and the movable bearing-plates f^2 are represented as tied to the shimming-blocks f^5 by central bolts f^9 , carried by the plates f^2 and working through the plates f^8 , with their heads movable in central slots f^{10} , formed in the blocks f^5 , as best shown in Fig. 3.

With the construction above described the movable plates f^2 , the springs f^4 , and the shimming-blocks f^5 are carried with the bolster in its lateral movement, while at the same time the said parts serve to support the bolster from the truck-frame with freedom for vertical movement on the springs f^4 . In this vertical movement of the bolster the movable bearing-plates f^2 rest constantly on the roller-bearings f' , with the guides g^5 of the bolster engaging the notches f^6 or other equivalent surfaces of the said plates f^2 . Hence perfect freedom is afforded for the spring action of the bolster. In virtue of the fact that the movable bearing-plates f^2 and the springs f^4 are carried with the bolster in its lateral movement, as above described, it must be obvious that the torsional strain on the springs f^4 is avoided. Otherwise stated, the springs f^4 occupy a constant position in the vertical plane in respect to the bolster and the plates f^2 on which the springs rest. The wear and tear of the springs is therefore very greatly reduced, as compared with the constructions hitherto used under the lateral motion. This improvement in the spring action is obtained without detracting in the least

from the freedom of the bolster for lateral movement on its roller-bearing. The said roller-bearings f' and their co-operating bearing-plates f^2 are by my present invention set in a somewhat different relation to the bolster-supporting springs, but in respect to the lateral motion of the bolster serve substantially the same function as where shown in my several prior patents, Nos. 370,758, 383,688, 433,063, 506,460, and 528,844. In none of my prior patents, however, were any of the bearing-plates mounted so as to permit vertical movement of the bearing-plates in respect to the bolster.

I believe that I am the first to provide any kind of construction whereby the bolster-supporting springs are carried with the bolster in its lateral movements, while at the same time having their bases of resistance on the truck-frame for supporting the bolster with freedom for spring-cushioned vertical movement, and I desire herein to claim the same in the broadest possible way as a pioneer invention.

The shimming-blocks f^5 are preferably made of wood, but may be of any suitable material, and serve to afford a ready means for adjusting the bolster and the car-body to different heights by simply inserting substitute shimming-blocks of the desired thickness.

The bolster may be regarded as provided near its ends with pockets for receiving the springs, shimming-blocks, and the movable members of the bearing-plates.

It will be understood, of course, that the details of the construction might be varied in many ways without departing from the spirit of my invention.

It should be further noted that the concave form of the roller-bearing seats insures the centering of the bolster in its normal position.

What I claim, and desire to secure by Letters Patent of the United States, is as follows:

1. The combination with a truck-frame, of a bolster mounted for both vertical and lateral movements on the same, as a base of resistance, base-plates carried by and fixed against lateral movement with respect to said bolster, but free for vertical movement thereon, and springs between said base-plates and said bolster, substantially as described.

2. The combination with a truck-frame and a bolster mounted thereon with freedom for lateral and vertical movements, of fixed roller-bearing plates on the truck-frame, rollers on said fixed plates, movable bearing-plates on said rollers, and bolster-supporting springs on said movable plates, with said movable plates and said springs carried with the bolster, in its lateral movement, but permitting vertical movement of the bolster, in respect to the plates, substantially as described.

3. The combination with a truck-frame, of a truck-bolster, provided with pockets near

its ends, roller-bearing plates fixed to the frame, rollers on said fixed plates, movable bearing-plates on said rollers, bolster-supporting springs on said movable plates, and 5 vertical guides, in the pockets of said bolster, engaging with said movable plates, whereby the movable plates and the springs are carried with the bolster, in its lateral movement, while permitting the vertical movement of 10 the bolster, in respect to said plates, substantially as described.

4. In a car-truck, the combination with the side frames, of the fixed bearing-plates f , the roller-bearings f' , the movable bearing-plates 15 f^2 , the springs f^4 , the shimming-blocks f^5 , and a bolster provided with pockets, for receiving said parts $f^2 f^4$ and f^5 , and provided with guides coöperating with the plates f^2 , substantially as and for the purpose set forth.

20 5. A car-truck bolster, composed of the

channel-bars g , cross-ties $g^2 g^3$ and end caps or filling-pieces g^4 , and having pockets in its ends equipped with vertical guides, in combination with the fixed bearing-plates f , the rollers f' , the bearing-plates f^2 , the springs 25 f^4 , and the shimming-blocks f^5 , all arranged, for coöperation, substantially as described.

6. The combination with the bolster-columns c' and the saddle-plates c^3 , of the gussets c^2 , binding said parts together and reinforcing the same, said parts being formed of separate pieces and united by rivets substantially as described.

In testimony whereof I affix my signature in presence of two witnesses.

JOHN C. BARBER.
